CLAIM

The ornamental design for a container lid, as shown and described.

DESCRIPTION

FIG. 1 is a perspective view taken from the top of a container lid of the design;

FIG. 2 is a front elevational view of the design of FIG. 1;
FIG. 3 is a back elevational view of the design of FIG. 1;
FIG. 4 is a right elevational view of the design of FIG. 1;
FIG. 5 is a left elevational view of the design of FIG. 1;
FIG. 6 is a top plan view of the design of FIG. 1;
FIG. 7 is a bottom plan view of the design of FIG. 1; and,
FIG. 8 is a perspective view showing the container lid of FIG. 1 as used in stacking two or more containers.

The broken lines in the drawings illustrate environmental subject matter only and form no part of the claimed design.
